UNITED STATES PATENT OFFICE.

HANNAH HEY, OF KANSAS CITY, MISSOURI.

FOLDING CURTAIN-DRYING FRAME AND PEDESTAL.

SPECIFICATION forming part of Letters Patent No. 576,981, dated February 9, 1897.

Application filed October 10, 1896. Serial No. 608,475. (No model.)

To all whom it may concern:

Be it known that I, HANNAH HEY, a citizen of the United States, residing at Kansas City, in the county of Jackson and State of Missouri, have invented a certain new and Improved Folding Curtain-Drying Frame and Pedestal; and I do hereby declare that the following is a full, clear, and exact description of the invention, such as will enable others to make and use the same, reference being had to the accompanying drawings, forming a part of this specification.

The object of my invention is an upright extensible frame for the support and convenient attachment thereto of fabrics for drying purposes, and which may be folded when not in use conjointly with a folding pedestal.

My invention consists in the novel construction and combination of parts, such as will first be fully described, and specifically pointed out in the claims.

Referring to the drawings, Figure 1 is a view in perspective of the improved curtain-supporting frame connected with the pedestal and with the separate parts extended and in position for use. Fig. 2 is a perspective view showing the separate parts of the frame adjusted in the direction of and folded in position in proximity to the pedestal and within the circumference of its base, also showing the circular table removably secured to the pedestal. Fig. 3 is a plan view of the folded frame and pedestal, as seen in Fig. 2, with the table removed, showing the opening in the pedestal for a pin on the under side of the table; Fig. 4, a sectional view of the table, showing its connecting-pin, and also a rear side view of the upper portion of the pedestal receiving the pin. Fig. 5 is a sectional view of the upper hinged portion of the pedestal, showing the adjusting-bolt within the V-shaped groove. Fig. 6 is a detail view in section of a portion of the standard and horizontal bar, showing the adjusting nut and bolt.

Similar letters of reference indicate corresponding parts in all the figures.

Referring to the drawings, A represents the pedestal, which, as shown in the drawings, consists of a rectangular-shaped post of equal dimensions between opposite ends and extending in height a distance twice that described by the ordinary corner-supports or

legs to a table. At a point equidistant from the ends the pedestal A is separated transversely into two parts a a', and hinged together upon the rear side by separate hinges a² a³, the hook and staple a⁴ on the front side keeping the pedestal in position. The lower end of the part a' of the pedestal is connected rigidly with the upper surface b, a base B, which, as shown, consists of a flat plank, extending in opposite directions a sufficient distance to give the requisite support to the pedestal.

To the front side of the pedestal A is connected the adjustable folding frame C, which is constructed as follows:

In the front side of the upper part a of the pedestal A, the parts being in position as in Fig. 1, is a V-shaped groove a⁴, which extends in the direction of the pedestal. In said groove is arranged adjustably the head of a screw-bolt a⁵, to which is fitted the nut a⁶. To the bolt a⁵ is attached one end of a longitudinally-slotted flat bar, which extends horizontally the described length in one direction laterally from the pedestal, and is separated transversely at a point nearly equidistant from the ends into two parts c c', and the parts hinged together by the extension leaf-hinges d d' on the front side of the said bars, one hinge being connected with the portions of the bar upon one side of the longitudinal slot and the other hinge with the portions of the bar on the other side of said slot, the joint of the said hinges being extended forward from the front side of the said bar at a distance slightly greater than that described by two of said bars placed flatwise one upon the other.

In the front side of the portion a' of the pedestal A, a short distance above the base B, is inserted a screw-bolt d², to which is adjustably attached one end of the longitudinally-slotted folding bars c² c³, which are constructed and hinged together by the hinges d³ d⁴ precisely in the same manner as the bars c c', and extend in the same direction from the pedestal A.

To the outer end and rear side portion of the bar c' is connected flatwise the upper end portion of a standard or bar D, by means of the adjusting-bolt d³ and nut d⁴, the bolt passing through the slots in the opposite bars.

The standard D is the same thickness as bar c' and is separated in two parts d⁵ d⁶ upon a line horizontal with the line of separation of the parts a a' of pedestal A, and said parts 5 hinged together by means of an extension leaf-hinge d⁷ on the back or rear side of said standard, the joint of which hinge extends rearwardly from the standard a distance corresponding to that described by the hinge a⁸ 10 on the pedestal A from the front side of said pedestal. The separate parts of the standard D are longitudinally slotted to a point a short distance from the hinge d⁷.

The lower end portion of standard D extends 15 downwardly to a point in line horizontally with the upper surface b of base B, and is secured adjustably to the rear side of the bar c³ by an adjusting bolt and nut, which is the same as bolt d³. To the rear side and 20 lower end of the standard D is pivotally attached one end of a short foot-plate d⁸, the other end of which extends to the floor.

To the screw-bolt a⁵, outside of the bar c, is attached a longitudinally-slotted bar of the 25 same described length as the hinged bars c c', and which extends in an opposite direction to said bars c c', and is separated transversely at a point equidistant from the ends into separate parts c⁴ c⁵, the said parts being hinged 30 together by ordinary leaf-hinges d⁹ d¹⁰, secured to the abutting ends of the separate parts of the bar, and one of said hinges d⁹ being above the slot and the other below the slot in said bar. To the screw-bolt d², overlapping the 35 end of bar c², is connected one end of a longitudinally-slotted bar, which extends in the opposite direction to the bar c² and is separated into two parts c⁶ c⁷, which are the same in length as the respective bars c⁴ c⁵, and 40 hinged together by the hinges d¹² d¹³ in precisely the same manner as the bars c⁴ c⁵.

To the rear side and at the ends of the respective bars c⁵ c⁷ is adjustably connected a slotted standard D', which is separable in 45 two parts d¹⁴ d¹⁵ and hinged together in precisely the same manner as the standard D. In the bars composing the frame are perforations c⁸ at suitable distance apart for the attachment of fabrics for drying, &c., particularly lace curtains, for which my improved 50 frame is especially applicable.

In employing the frame C for the uses above referred to the curtains in a damp condition are first connected with the bars c c' c⁴ c⁵, and 55 for this purpose the adjusting-nuts upon the bolts connecting said bars with the pedestal and standard are loosened and the bars lowered in position. The longer side of the curtain is then secured in any well-known manner lengthwise to the said bars c c' c⁴ c⁵. When 60 this is accomplished, the other side of the curtain is secured to the bars c² c³ c⁶ c⁷ and the upper bars raised in position, stretching the curtain to the full extent. The bars are then 65 secured in position by tightening the bolts. For the purpose of stretching the curtains lengthwise the same adjustment is made of

the standards D D' as described of the bars c c' c⁴ c⁵, the curtain being first secured to one or the other standard. For the drying 70 of fabrics of all kinds the frame may be adjusted to certain widths of the cloth, such as calicoes and cloths printed in narrow widths and short lengths, the standards being adjustable, so as to accommodate articles which require stretching while drying of small dimensions. In this manner shrinkage is prevented 75 which otherwise occurs in certain kinds of goods or fabrics.

For the purpose of folding the separate 80 parts of the frame and the pedestal when the frame is not in use the adjusting-nuts are loosened, connecting the standards D D' with the respective horizontal upper and lower bars c' c³ c⁵ c⁷. The standard D is moved in 85 position to a point a short distance from the pedestal A, as seen in dotted lines in Fig. 1, the adjusting-bolts passing between the hinges d d' d⁰ d⁸. The plate d⁸ is raised a short distance and the lower end of the standard 90 rests upon the upper surface b of base B. The standard D is also moved in the direction of the pedestal to a position the like distance from the pedestal as described of standard D. The overlapping upper bars c c⁴ are 95 moved so as to bring the ends of the separate bars at nearly equal distances from the bolt a⁵, and the bars c³ c⁶ likewise from bolt d². The bar c⁵ is moved rearwardly and folded upon bar c⁴ and the bar c⁷ moved in the same 100 direction and folded upon the bar c⁶. The bar c' is then moved forward and folded upon the bar c⁵ and the bar c³ moved in the same direction and folded upon the bar c⁷. The hook a⁸ is released from its staple on the 105 part a' of the pedestal and the folded parts of the frame and the hinged portion a of the pedestal moved upon the hinged connections a³ a² rearwardly, the part a of the pedestal 110 folding upon the part a', and the adjustable and hinged bars brought into the position as seen in Fig. 2, compact and within the circumference of the base B.

To further utilize the pedestal, a vertical 115 perforation or groove e is made in the opposing surfaces of the folded upper parts a a' of the pedestal between hinges a² a³. A table E is provided with a pin e' upon its under side and fitted within the groove or perforation e in the pedestal, whereby an article of 120 furniture is afforded upon which the fabrics may be ironed.

Instead of a flat base B, I may provide the pedestal with legs, and thus do away with a 125 foot-plate d⁸ upon the lower end of the standards D D', the standards then being made long enough to reach the floor and extending when in a folded position between the legs of the pedestal. The bars composing the frame are made of equal thickness and, as 130 shown, from light material, such as wood. The pedestal may be made from metal and of the same thickness as the horizontal bars, in which case the extension leaf-hinge would

not be required to extend as far rearwardly to compensate for the thickness of the pedestal when in a folded position. I may employ the frame separate from the pedestal when 5 required.

Having fully described my invention, what I now claim as new, and desire to secure by Letters Patent, is—

1. A folding drying-frame for fabrics, its 10 sides being composed of longitudinally-slotted bars, each bar having separate overlapping, adjustable folding parts and extension-hinges connecting said folding parts at one end of said frame, and the ends of said frame 15 composed of longitudinally-slotted standards, each standard having separate folding parts and extension-hinges connecting each part as and for the purpose described.

2. A folding drying-frame for fabrics, its 20 sides being composed of longitudinally-slotted bars, each bar having separate overlapping, adjustable and folding parts and extension-hinges connecting said folding parts at one end of said frame, and the ends of said 25 frame composed of standards, each standard having separate folding parts and extension-hinges connecting each part, and a pedestal connected with the said frame having separate folding parts hinged together upon a line 30 horizontal with the hinged joint of the said standards as and for the purpose described.

3. A folding drying-frame for fabrics, its 35 sides being composed of longitudinally-slotted bars, each bar having separate overlapping, adjustable and hinged folding parts,

and extension-hinges connected with said folding parts at one end of said frame, and the ends of said frame composed of standards, each standard having separate folding parts and extension-hinges connecting each part, 40 a pedestal connected with the adjustable bars of said frame, having separate folding parts hinged together upon a line horizontal with the hinged joint of the said standards, upon 45 the rear side and a fastening device upon the front side, and means for adjusting the said bars upon the pedestal as and for the purpose described.

4. The combined drying-frame and pedestal, 50 said frame being composed of longitudinally-slotted bars, each bar having separate overlapping, adjustable and hinged parts, and extension-hinges connecting one of said parts at one end of said frame, and the ends of said frame composed of standards, each standard 55 having separate folding parts and extension-hinges connecting each part, and adjusting nuts and bolts connecting said standards and said bars, said pedestal having separate folding parts hinged together upon a horizontal 60 line with the joints of the hinges in said standards, and provided with a vertical groove upon its front side, adjusting bolts and nuts in said groove connected with the adjustable parts of said bars, and a base for said pedestal as and 65 for the purpose described.

HANNAH HEY.
